JOHN J. HEYS, OF LYNN, MASSACHUSETTS, ASSIGNOR TO UNITED SHOE MACHINERY COMPANY, OF PATERSON, NEW JERSEY, A CORPORATION OF NEW JERSEY.

METHOD OF PREPARING OUTSOLES.

1,137,618.

Specification of Letters Patent. Patented Apr. 27, 1915.

Application filed July 27, 1914. Serial No. 853,384.

To all whom it may concern:

Be it known that I, JOHN J. HEYS, a citizen of the United States, residing at No. 45 Nahant street, Lynn, in the county of Essex and State of Massachusetts, have invented 5 certain new and useful Improvements in Methods of Preparing Outsoles; and I do hereby declare the following to be a full, clear, and exact description of the invention, 10 such as will enable others skilled in the art to which it appertains to make and use the same.

This invention relates to a novel method 15 of preparing outsoles for incorporation in boots and shoes.

In preparing an outsole for a Goodyear welt, McKay or shoe of like construction, it 20 is desirable to perform what is known as the "shanking-out" or "feather edging" operation. By this operation a portion of the edge of the sole blank, more generally the shank, is skived along the opposite margins, on the flesh side, resulting in a light edge 25 at the shank or elsewhere which, among other advantages, imparts a better finish to the shoe.

The shank skivings for correct shoe making, are extended forward along the margin of the shank to the ends to the ball line, and 30 rearward to the ends of the breast line. This shanking-out operation and resultant appearance given to the outsole is especially desirable when the outsole is molded, as has lately come to be the practice, with distinctly sharp and defined lines to give character and pronounced shape to the bottom 35 of the shoe. In preparing soles of this character at present, the desired shape of the sole is obtained by placing the flat sole 40 blank in a sole molding machine having suitably fitted molds, the flat blank first, however, having been operated on by the shanking-out or feather-edging machine. Serious difficulties have been encountered in 45 practising this method of preparing outsoles. It is the commercial practice, for reasons thoroughly familiar to those skilled in the art, to utilize a single pair of sole molds for a wide range of sizes and widths 50 of outsoles. The common practice is to use but a single pair of molds for all soles of any one style operated upon, for example, size 2 to 8 women's work, and size 7 (some-

times 5) to 13 men's work. Furthermore, 55 all widths of sole sizes of one style are covered in one pair of molds. It is obvious that however the molds may be fitted they cannot give the correct and required exact shape to all the various sizes and widths upon which they are caused to operate. 60

The disadvantage of shanking-out the sole blank, before molding it, is obvious 65 from the following consideration. The molds cannot be made to fit exactly more than one size of shanked-out sole in one width. As the location of the shank skiving is determined by the eye of the operative it frequently happens that the forward 70 end of the skiving is not at the exact point that should define the shank from the forepart, resulting in a dull and indistinct molding, as the substance has been removed and consequently the molds cannot fit, or the substance exists where it should have been removed, and the edge of the sole is consequently squeezed out of shape. The result is a 75 cripple.

The object of the present invention is to provide a method of preparing molded outsoles for boots and shoes which will overcome the disadvantages of the method which is now the common practice. 80

In accordance with this object it is proposed to mold the outsole to the desired shape while its shank is composed of an even amount of stock, that is, before the stock at the shank is reduced by being skived, for then the molds now in use for different styles can be made to fit all widths 85 with equal exactness. Under these conditions, by accurately placing the unskived sole between the molds, the exact ball line can be located and thus place the line of demarcation, that gives snap and character 90 to the shoe, in its proper position between the shank and forepart. The result is a sharply defined line, or break, on the sole at the exact, desired location. After molding the sole, the shank can readily be reduced to the desired thickness, by the shanking-out or feather-edging operation, without losing any of the sharply-defined molding lines. A further feature resulting from 95 the practice of this method, resides in the provision of a guide, namely, the sharp 100 break caused by the molded lines, at the ball 105

line, by means of which the shanking-out operative accurately determines the termination of the forward ends of the shank skivings, and the distance of inward cut.

5 To the accomplishment of this object, the present invention consists in the novel method of preparing outsoles, the preferred manner of practising which is herein described and defined in the appended claims.

10 The advantages of the method will be further explained by reference to the accompanying drawings in which,

Figure 1 is a perspective showing the grain side of an outsole properly molded for 15 a diamond ball and cottage shank, showing the first step of the present novel method; Fig. 2 is a perspective showing the flesh side of the molded sole shown in Fig. 1, the shank, however, having been feather-edged in accordance with the second step of 20 the present novel method; Fig. 3 is a plan of the shank portion of the grain side of a sole which has been molded for a circle ball and cottage shank after having been feather-edged, showing the defective pressure under 25 the old method; Fig. 4 is a perspective of a portion of a sole which has been molded after having been feather-edged, showing the defect under the old method due to making the shank skiving too short, and Fig. 5 30 is a side elevation of the sole portion shown in Fig. 4.

While the figures of the drawings all show, for clearness, dinked out outsoles, it 35 is obvious that the invention is useful in preparing any blocked stock outsole in commercial use.

Referring to the drawings it will be noted that the shank portion of the sole in Fig. 1 40 is shown as composed of an even thickness of stock throughout, that is, the edge 1 is of the same thickness from ball to heel seat. A sole of this character receives the full molding pressure on its shank from all portions 45 of the molds, the lines of the break, 2 at the ball and 3 along the shank, being sharp and well defined, and the shank itself stiffened so that it will hold its shape. In Fig. 3, however, a portion of a sole is shown 50 which has been feather-edged before being molded in accordance with the old method. In this figure the darkened portion 4 indicates pressure from the molds and the light portions 5 indicate that no molding pressure 55 has been applied to these portions of the sole. This results from the feather-edged sole not fitting the molds, and is disadvantageous in that the fibers in the marginal portions of the shank are not thoroughly compacted as is desirable. A sole 60 prepared in this manner has a soft, flimsy shank which will not hold its shape.

In Fig. 2 there is shown a molded sole 65 which has been molded and then feather-edged by the present method, it being espe-

cially noted that the thin edge of the shank, indicated at 6, extends as is proper right up to the break at the ball line. Compare the appearance of this sole with that shown in Fig. 5. In the sole of Fig. 5 the feather-edging operation was performed before molding and the skiving 7 was not carried far enough forward, resulting in the retention of the thick edge portion 8 just in the rear of the ball line which portion should 70 have been thinned like the remainder of the shank edge for a neat appearing shank on the finished shoe.

Fig. 4 shows a sole like that in Fig. 5 75 molded after feather-edging in molds which have been fitted to provide for the molding pressure on a properly shanked-out sole. In the sole illustrated the feather-edging operation was not carried far enough forward at the inside shank with the result 80 that during molding the margin of the shank just at the rear of the inside ball is crushed and squeezed into a lump. Had the skiving been carried too far forward, as frequently happens, the break in the sole would 85 not have been sharp and distinct.

By utilizing the present novel method of first molding an outsole blank while its shank is composed of an even amount of stock and thereafter feather-edging, all of 90 the various causes of cripples hereinbefore referred to are eliminated and perfect work in all instances is the result while still retaining the use in the sole molding machine of but a single pair of molds for all sizes 95 of one style as is desired by shoe manufacturers. Those skilled in the art will perceive that the exact time when the feather-edging operation is performed is immaterial, that is, other operations may be performed before feather-edging, the essential feature being that the sole blank be molded first.

I believe I am the first to prepare outsoles 100 by the method herein described, and those skilled in the art will readily recognize that the present novel method of preparing outsoles affords an organized method of manufacture which is simple, enables outsoles to be prepared with greater economy, and produces a better and more uniform product 105 than it has been possible to obtain heretofore.

What is claimed as new, is:

1. The method of preparing outsoles for 110 incorporation in boots and shoes which consists in first molding the block stock to the desired shape, and thereafter feather-edging the molded sole.

2. The method of preparing outsoles 115 which consists in first molding the sole blank while it is composed of an even amount of stock in the shank, and thereafter reducing the shank of the molded sole.

3. The method of preparing outsoles 120

which consists in first molding a sharply defined break or line of demarcation at the ball line between the shank and forepart, and thereafter reducing the shank of the 5 molded sole in the rear of said break.

4. The method of preparing outsoles which consists in first molding the sole blank to produce a break at the ball line,

and thereafter reducing the shank of the molded sole, said break forming a guide to determine the forward extent of the shank reduction.
